Primary Examiner — Ricky Pham(74) *Attorney, Agent, or Firm* — Faegre Baker Daniels LLP**CLAIM**

The ornamental design for an oven bracket, as shown and described.

DESCRIPTION

FIG. 1 is a front perspective view of an oven bracket illustrating my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view thereof; and,

FIG. 9 is a front perspective view of the oven bracket coupled to an optional oven.

(Continued)

Broken lines illustrate an optional environment of an oven that forms no part of the claimed design.

1 Claim, 8 Drawing Sheets
